UNITED STATES PATENT OFFICE.

JOHN A. BACH, OF PHILADELPHIA, PENNSYLVANIA.

CIGAR BUNCHING AND WRAPPING MACHINE.

No. 856,201.

Specification of Letters Patent.

Patented June 11, 1907.

Application filed June 16, 1906. Serial No. 321,966.

To all whom it may concern:

Be it known that I, JOHN A. BACH, a citizen of the United States, residing at the city of Philadelphia, in the county of Philadelphia and State of Pennsylvania, have invented certain new and useful Improvements in Cigar Bunching and Wrapping Machines, of which the following is a specification.

10 My invention has relation to a cigar bunching and wrapping machine; and in such connection it relates more particularly to the construction and arrangement of a yielding table, an endless wrapping apron and rollers 15 for guiding and for forming in conjunction with the apron, pockets which parts in cooperating increase the length of rolling movement imparted to the tobacco form a more evenly rolled bunch and prevent unraveling of the wrapper during discharge of 20 the partially formed cigar, from the machine.

The principal objects of my invention are first, to provide the cigar bunching and wrapping machine with an endless wrapping 25 apron which is adapted to be moved forward during a portion of the bunching and wrapping of the tobacco and is adapted to remain stationary during the backward movement 30 of the bunching roller to prevent unraveling 35 of a portion of the wrapper at the backward movement of the apron and also to prevent undue or quick wear of the apron by the continuous presentation of successive portions of the same to the bunching roller; second, to 40 provide a bunching and wrapping machine with an arched table yielding in vertical and horizontal planes to permit the same, when subjected to pressure, by the hand of an operator, to immediately close the pocket formed 45 by the apron and bunching roller to increase the length of rolling movement imparted to the tobacco by the apron and to thus produce a more evenly rolled cigar; third, to provide the machine with means to tighten and 50 loosen the wrapping apron so as to permit of the formation of a smaller or larger pocket into which the loose tobacco is placed prior to bunching and wrapping of the same and thus to permit of the manufacture of thicker 55 or thinner cigars; fourth, to so arrange one of the guide rollers for the apron as to form a receiving pocket for catching the partially finished cigar so as to maintain the same in a completely rolled condition; and

fifth, to provide the base of the machine with 55 means for holding the same and thus the table in an oblique or inclined position to permit the operator in a sitting position to observe the introduction and proper distribution of the tobacco to be bunched into 60 the pocket formed by the apron.

The nature and scope of my invention will be more fully understood from the following description taken in connection with the accompanying drawings forming part hereof, 65 in which

Figure 1, is a view, illustrating in vertical section, the inclined base of the bunching and wrapping machine, the yielding arched table formed of a sheet of metal secured thereto, 70 an endless apron, the manner of forming the bunching pocket for the tobacco and the receiving pocket for the partially finished cigar, all embodying main features of my present invention. Fig: 2, is a top or plan 75 view of the machine. Fig: 3, is a view illustrating in side elevation, the machine and the adjustable support of certain of the guide rollers of the wrapping apron to increase or decrease the size of the bunching pocket. 80 Fig: 4, is a cross-sectional view of the machine on the line x—x of Fig: 1; and Figs: 5, 85 6 and 7 are sectional views, illustrating the different outlines of the table, which the same assumes, when subjected to pressure by 85 the bunching roller and the hand of the operator during the bunching and wrapping operations.

Referring to the drawings, *a*, represents the base of the machine, which by means of 90 standards or feet *a*¹ and *a*², is held in an oblique or inclined position. As shown in Figs: 1 and 4, the base *a*, is provided with a slot *a*³, through which passes an endless apron *b*, of suitable material and predetermined length. 95 Outside the base *a*, the apron *b*, is conducted over guide rollers *c* and *c*¹, arranged at one end of the base *a*, then beneath a bail *d*, and over a bunching roller *e*, carried by the bail *d*, then over a yielding or flexible table *f*, and 100 over a guide roller *g*, carried by brackets *h*, secured to the base *a*, opposite the rollers *c* and *c*¹. The table *f*, preferably, consists of a thin sheet of brass, which is bent so as to form an arched or curved top portion *f*¹, and 105 straight portions *f*², and *f*³, terminating in right angular portions *f*⁴ and *f*⁵, which rest directly upon the base *a*, and to which the

table f , is secured in any suitable manner. The bail d , in the points d' , is pivotally connected with the base a , and the arrangement of the bunching roller e , carried thereby is such that when the same forces the apron b , down upon the arched portion f^1 , of the table f , the table will be slightly distorted in its outline, for a purpose to be presently more fully described.

10 In a normal or inoperative position, the bunching roller e , rests upon the base a , and the apron b , depressed between the roller e , and the table f , rests in the present instance, on the extensions f^4 , thereof, thus forming a pocket i , into which the operator places the loose tobacco to form the bunch, while upon the apron resting on the side f^2 , and arched portion f^1 , of the table f , are placed the leaf of tobacco, which is to form the binder wrapper, into which the loose tobacco leaves are rolled, in the usual well known manner. After the loose tobacco leaves have been placed and properly distributed in the pocket i , which manipulation owing to the inclined position of the base a , can be observed by the operator in a sitting position, the bail d , is first slightly raised and the table f , by the pressure of the hand of the operator, is moved or shifted rearward, into the position shown in Fig: 5. In this shifted position of the table f , the same will immediately close the pocket i , formed in the apron b , by the roller e , and table f , and thus by the further movement of the roller e , the rolling movement imparted to the tobacco by the apron b , will immediately begin, thereby appreciably increasing the length of travel of the tobacco to be bunched and wrapped. The increase in the length of the rolling movement imparted to the tobacco is due to the immediate closing of the pocket i , which insures the proper bunching of the same, and the immediate rolling of the tobacco into wrapped leaves, thus producing a more evenly rolled cigar. This even rolling of the cigar is further rendered possible, by the yielding of the table f , which is released by the operator as soon as the bunching roller e , has reached the arched portion f^1 , of the table f , in which position the pocket i , will now be held closed by the table f , as shown in Fig: 6. This closing of the pocket i , will be maintained even when the roller e , has left the arched portion f^1 , of the table f , and reached the straight portion f^3 , of the same, as in this instance the table under the pressure of the roller e , is again swung rearward into the position shown in Fig: 7, until the end of the straight portion f^3 , and the extension f^5 , of the table f , is reached, in which instance the table f , moves back into its normal position, as shown in Figs: 1 and 3. In the end position of the bunching roller e , at the front of the machine, the same rests directly upon the guide roller g , for the apron b , which roller g ,

in conjunction with the bunching roller e , and the extension f^5 , of the table f , forms a receiving pocket k , for the now partially finished cigar l , as shown in dotted lines in Fig: 1. This pocket k , which is released from any pressure by the table f , is of such a shape, that during the backward movement of the bunching roller e , into the initial or inoperative position shown in Fig: 1, the same is first gradually and then quickly opened. During the latter portion of the opening of the pocket a slight rolling movement is imparted to the partially finished cigar l , in the same direction as had been previously imparted to the tobacco under the direct influence of the bunching roller e . This rolling movement is rendered possible as the apron b , is not moved backward by the bunching roller e , and thus the unraveling of the wrapper of the cigar l , by the apron b , is effectually prevented.

To the apron b , during the forward movement of the bunching roller e , to close the pocket i , is imparted a slight forward movement which, however, ceases as soon as the bunching roller e , presses the apron b , upon the arched portion f^1 , of the table f , in which instance the friction produced between the apron and table prevents any further movement of the apron b , from left to right, in Fig: 1. During the backward movement of the bunching roller e , the apron b , is not actuated or moved backward but remains stationary, which stopping of the movement of the apron, as hereinbefore described, aids in the imparting of a slight rolling movement to the cigar l , during its discharge from the machine. By the forward movement of the apron b , in one direction, successive portions of the same are continuously presented to the bunching roller e , and thus a quick wear of the apron is effectually prevented.

In order to increase or decrease the size of the pocket i , formed in the apron b , by the bunching roller e , and table f , the guide rollers c and c' , are supported by brackets m and m^1 , which, by means of clamping bolts n , passing through slots m^2 , thereof, are adjustably connected with the base a , as shown in Fig: 3. By the loosening of the bolts n , the brackets m and m^1 , and by the same the guide rollers c and c' , may be shifted toward or away from the base a , by which movement of the rollers, the apron b , will be correspondingly tightened or loosened. This loosening or tightening of the apron b , by the guide rollers c and c' , permits of the formation of a pocket i , of larger or smaller diameter in the same and thus of the manufacture of thinner or thicker cigars.

Having thus described the nature and objects of my invention, what I claim as new and desire to secure by Letters Patent is:—

1. In a cigar bunching and wrapping machine, a base, a table having an arched top and substantially straight ends consisting of a sheet of metal carried by said base, said ta-

ble adapted when subjected to pressure to change the outline of the arched top and of the straight ends of said table.

2. In a cigar bunching and wrapping machine, a base, a table having an arched top and substantially straight ends, consisting of a sheet of metal carried by said base, said table adapted when subjected to pressure to yield in vertical and swing in horizontal planes on said base.

3. In a cigar bunching and wrapping machine, a base, a table having an arched top and substantially straight ends consisting of a sheet of metal carried by said base, and an endless wrapping apron held in position on said table by said base.

4. In a cigar bunching and wrapping machine, a base, a bunching roller, means for supporting said roller, a table having an arched top and substantially straight ends carried by said base, an endless wrapping apron held in position on said table and roller by said base, and said apron adapted to be shifted during the movement of said roller in one direction.

5. In a cigar bunching and wrapping machine, a base, a bunching roller, means for supporting said roller, a table yielding in vertical and horizontal planes carried by said base, a wrapping apron passing over said roller and table, said apron adapted to form between said roller and table a pocket for the reception of tobacco to be bunched, and said table adapted when the arched top is swung rearward to close said pocket.

6. In a cigar bunching and wrapping machine, a base, a bunching roller, means for supporting and actuating said roller, a table having an arched top and substantially straight ends and adapted to yield in vertical and horizontal planes carried by said base, an apron passing over said roller and said table and adapted to form in conjunction therewith, a pocket for tobacco to be bunched, and said table adapted when yielding in a horizontal plane to move rearward so as to close the pocket prior to the closing thereof by the arched portion of said table.

7. In a cigar bunching and wrapping machine, a base, a table having an arched top and substantially straight ends consisting of a sheet of metal carried by said base, a bunching roller, means for supporting and actuating said roller, an apron held in position by said base and passing over said roller and table, and means for holding said base and by the same said table in an inclined position.

8. In a cigar bunching and wrapping machine, a base, a table having an arched top and substantially straight ends, consisting of a sheet of metal carried by said base, a bunching roller, means for supporting and connecting said roller with said base, an endless apron held in position by said base and adapted to form a pocket for loose tobacco

between said roller and table, and means adjustably connected with said base and partially supporting said apron, said means adapted when adjusted to tighten and loosen said apron so as to increase or decrease the size of the pocket to be formed by said apron.

9. In a cigar bunching and wrapping machine, a base, a table carried by said base, a bunching roller, means for supporting and moving said roller over said table, a guide roller carried by said base, an apron connected with said base and passing over said table and bunching and guide rollers, said rollers adapted, when occupying a position in proximity to each other, to permit of the formation of a receiving pocket for a cigar by said apron and said bunching roller adapted when returned to an inoperative position to gradually open the pocket and to impart to the cigar, during its discharge, a slight rolling movement by the apron.

10. In a cigar bunching and wrapping machine, a base, a table having an arched top and arranged to yield in horizontal and vertical planes, carried by said base, a guide-roller supported by said base, a bunching roller, means for supporting and holding said bunching roller in proximity to the arched top of said table, when moved over the same, an apron connected with said base and passing over said table and bunching and guide roller, said apron adapted to form in the inoperative position of said bunching roller between the same and table a pocket for tobacco to be bunched, said table when subjected to manual pressure adapted to close said pocket in conjunction with said bunching roller prior to the closing of the same by the arched top of said table, to increase the length of travel of said bunching roller over the same, said bunching roller when shifted into proximity and away from said guide-roller adapted to permit of the formation of a receiving pocket for the bunched tobacco by said apron and to impart a rolling movement to the same during the opening of the pocket.

11. In a cigar bunching and wrapping machine, a base, a table having an arched top and substantially straight ends, consisting of a sheet of metal carried by said base, an endless wrapping apron passing over said table and adapted to form pockets for the reception of loose and bunched tobacco and a bunching roller for shifting said apron for a predetermined distance in one direction and for rolling the tobacco by the apron over said table.

12. In a cigar bunching and wrapping machine, a base, a table, consisting of a sheet of metal carried by said base, an endless wrapping apron passing over said table and adapted to form pockets for the reception of loose and bunched tobacco and a bunching roller for shifting said apron for a predetermined dis-

- tance in one direction and for rolling the tobacco by the apron over said table, and said apron when shifted adapted to present successive portions of the surface thereof to said 5 bunching roller.
13. In a cigar bunching and wrapping machine, a stationary base, a table, consisting of a sheet of metal bent so as to form arched and substantially straight portions, carried 10 by said base, an endless wrapping apron held in proper position on said table by said base, and means carried by said base and adapted to guide the apron over the ends of said base and certain of said means adapted when ad- 15 justed in their position with respect to said base, to increase or decrease the length of the portion of said apron passing over the base and table.
14. In a cigar bunching and wrapping ma- 20 chine, a stationary base, a table consisting of a sheet of metal bent to form an arched top carried by said base, an endless wrapping apron passing over said table and adapted to be held in position thereon by said base, a 25 bunching roller adapted in conjunction with said table to permit of the formation of pockets by said apron, and said table adapted when subjected to manual pressure and to pressure by said roller to yield in vertical 30 and horizontal planes.
15. In a cigar bunching and wrapping ma- 20 chine, a stationary base having a slot, rollers carried by said base, a table having an arched top supported by said base, an endless apron 35 passing through the slot of said base and over said rollers and table, certain of said rollers adapted when shifted as to their position, with respect to said base, to tighten or loosen said apron.
16. In a cigar bunching and wrapping ma- 40 chine, a stationary base having a slot, a yielding shifttable table having an arched top and substantially straight ends carried by said base, guide rollers secured to each end 45 of said base, means for holding said base and by the same said table in an inclined position, an endless apron passing through the slot of said base and over said guide rollers and table, certain of said guide rollers adapt- 50 ed when shifted, as to their position with respect to said base, to tighten or loosen said apron.
17. In a cigar bunching and wrapping ma- 55 chine, a base having a slot, a table, consisting of a sheet of metal bent to form an arched top and substantially straight end portions
- carried by said base, guide rollers secured to said base, a bunching roller, means for movably connecting said roller with said base, an endless apron passing through the slot of 60 said base and over said guide and bunching rollers and table, said bunching roller and one of the straight ends of said table adapted to permit of the formation of a pocket for tobacco in said apron, and said table adapted 65 when subjected to manual pressure to swing rearward to close said pocket.
18. In a cigar bunching and wrapping ma- 70 chine, a base having a slot, a table consisting of a sheet of metal bent to form an arched top and substantially straight ends carried by said base, guide rollers secured to said base, a bunching roller, a bail for movably connecting said roller with said base, and for holding the same in engagement with the 75 arched top of said table when moved over the same, an endless apron passing through the slot of said base and between said bail and said guide and bunching roller and table, said apron adapted to permit of the forma- 80 tion of a pocket for tobacco in the same and said table adapted when subjected to manual pressure to swing rearward to close the pocket in said apron prior to the closing of the same by the arched top thereof. 85
19. In a cigar bunching and wrapping ma- 90 chine, a base having a slot, a table consisting of a sheet of metal bent to form an arched top and substantially straight ends carried by said base, guide rollers secured to said 95 base, a bunching roller, a bail for movably connecting said roller with said base, and for holding the same in engagement with the arched top of said table when moved over the same, an endless apron passing through a 100 slot formed in said base and said bail and over said guide and bunching roller and table, said apron adapted to permit of the formation of a pocket for tobacco in the same and said table adapted when subjected to 105 manual pressure to swing rearward to close the pocket in said apron prior to the closing of the same by the arched top thereof, and means for holding said base and by the same said table in an inclined position. 105
